ATTORNEY

UNITED STATES PATENT OFFICE.

JOHN H. BARLOW, OF NEW HAVEN, CONNECTICUT.

CARTRIDGE IMPLEMENT.

SPECIFICATION forming part of Letters Patent No. 293,297, dated February 12, 1884.

Application filed December 20, 1883. (No model.)

To all whom it may concern:

Be it known that I, JOHN H. BARLOW, a citizen of the United States, residing at New Haven, in the county of New Haven and State of Connecticut, have invented certain new and useful Improvements in Cartridge-Reloading Implements, of which the following is a specification, reference being had therein to the accompanying drawings.

10 My invention relates to implements or tools used in reloading cartridges, and is adapted more especially for that class of cartridges which are used in breech-loading shot-guns; and the invention consists of providing a means 15 for removing the exploded primer, for inserting a new primer in the primer-seat of the cartridge-shell, and a rammer for placing the wad into the shell, all combined in one implement of a very compact form.

20 Figure 1 is a view of my improved implement, partly in section, also illustrating the position of the cartridge-shell when inserting a new primer. Fig. 2 represents the implement inserted in a shell about to extract the 25 primer. Fig. 3 is a view of the sleeve, which serves as a rammer. Fig. 4 is a cross-section on line *x x* of Fig. 3.

While these reloading implements have been made heretofore in a variety of forms, I prefer 30 the one shown and hereinafter described.

The design of this invention is to furnish a combination-tool for loading shot-cartridges which shall embody simplicity, compactness, utility, and ease of manipulation, and this is 35 achieved in the construction and arrangement of the parts, substantially as and for the purpose hereinafter shown and described.

Letters of like name and kind refer to like parts in each of the figures.

40 As a certain amount of pressure is necessary in loading these cartridges, the body *A* of the implement is provided with a suitable convex head, *b*, which fits the hollow of the hand, enabling the operator to apply great power with little inconvenience to himself. This hand-piece *a* is located upon the body *A*, directly opposite to the piston *b*, which is more fully explained hereinafter.

In Fig. 1 *B* represents a cartridge-shell, with 45 a portion broken out to facilitate showing the parts, as seated in the recess of the implement

to insert a primer. This recess will be better understood by reference to Figs. 1 and 2 in conjunction, in which the lines *c* and *c* represent the open space above the cartridge-head, 55 *d* and *d* the sides of the recess fitting the external diameter of the cartridge-shell, and *e* and *e* the beveled enlargement corresponding to the head of the cartridge-shell. While this recess might be cut through, leaving the opposite sides parallel and permitting the shell to be entered from either side, I prefer making it as represented, with one end closed, which serves as a stop to center the shell directly under the primer-inserting screw *C*. 60

D is a sleeve, which forms the rammer for placing the wad into the shell, and when extended from the body *A*, as shown in section, Fig. 1, it is adapted to be rotated upon the piston *b*.

In Fig. 3 the sleeve *D* is represented as having fluted sides—a form which I do not strictly confine myself to, as a plain cylindrical sleeve will perform the work equally as well. Should it be desirable to make the sleeve *D* of metal, the fluted form would be the lightest in weight. The central hole passing longitudinally through this sleeve *D* is enlarged at one end, so as to leave a shoulder, *g*, as shown by dotted lines in Fig. 3, and also in the sectional view of Fig. 1. The function of this shoulder *g* on the inside of the sleeve *D* is set forth hereinafter. A side view is given of the piston *b* in Fig. 1, in which the projections *w w* (shown in dotted lines in Fig. 2) do not appear in outline, as they have a thickness the same as the diameter of the piston *b*, of which they are a part, and are adapted to fit into the transverse slot or opening *f* in the end of the sleeve *D*. The helical spring upon the piston *b* is retained 70 inside the sleeve *D* by the nut *r* upon the end of the piston *b*, one end of this spring pressing against the nut *r* and the other against the shoulder *g*, thereby keeping the sleeve *D* pressed toward the head or body *A*. A suitable pin is placed in the end of the piston *b* and secured by a screw—a device too familiarly known to need description.

Having described the several parts which constitute my invention, the operation and 80 functions of the same are as follows, viz: If it is desired to extract the primer from the

primer-seat in the cartridge-shell, the sleeve D should be turned upon the piston b until the slot or opening f is opposite the projections n n, when the helical spring upon the piston b will force the sleeve D into the position in Fig. 2, leaving the pin in the end of the piston protruding, which can be entered into the small hole in the center of the primer-seat, and the primer is forced out by pressure upon the convex hand-piece a. Should the tool be desired to operate as a wad-rammer, the sleeve D is moved longitudinally upon the piston b, so as to compress the helical spring and withdraw the projections n n from the slot f, when it is necessary to rotate the sleeve D one-quarter of a revolution upon the piston, thereby placing the end of the sleeve D against the projections n n, as in Fig. 1, in which position the other end of the sleeve covers and protects the extractor-pin from injury, and forms a very desirable form of wad-rammer. Whenever it is required to reseat a primer, (the primer first being placed in the pocket of the shell B,) the shell is passed into the recess in the body A, as shown in Fig. 1, the open space above the head of the shell allowing the primer, which has not been seated, to pass under the seating-screw C. With this seating-screw C the primer is forced into the pocket of the

shell, the rim of the shell which forms the 30 head being larger in diameter than the body proper, and entered into the enlargement of the recess. The shell B is thus held securely while the primer is being seated.

The sleeve D is shown in Fig. 3 as provided 35 with a small aperture, s, through which a screw-driver may be entered to remove the extractor-pin from the piston b without disturbing the other parts of the implement.

What I claim as new, and desire to secure by 40 Letters Patent, is—

In a cartridge-reloading implement, the combination of the body A, having a suitable recess upon one side for receiving and holding the head of the cartridge-shell B while seating 45 a primer, also provided with the primer-seating screw C or its equivalent, and convex hand-piece a, with the piston b, provided with an extractor-pin, as shown, together with the movable rammer-sleeve D, all being arranged 50 to operate substantially as and for the purpose set forth.

In testimony whereof I affix my signature in presence of two witnesses.

JOHN H. BARLOW.
